US0D1046447S

(12) **United States Design Patent** (10) Patent No.: **US D1,046,447 S**
(45) Date of Patent: ** Oct. 15, 2024

(54) **BAG**

(71) Applicant: **YETI Coolers, LLC**, Austin, TX (US)

(72) Inventors: **Roy Joseph Seiders**, Austin, TX (US);
Dustin Bullock, Austin, TX (US)

(73) Assignee: **YETI Coolers, LLC**, Austin, TX (US)

(*) Notice: Patent file contains an affidavit/declaration
under 37 CFR 1.130(b).

(**) Term: **15 Years**

(21) Appl. No.: **29/796,942**

(22) Filed: **Jun. 28, 2021**

Related U.S. Application Data

(63) Continuation of application No. 29/739,007, filed on
Jun. 22, 2020, now Pat. No. Des. 923,323, which is a

(57) **CLAIM**

The ornamental design for a bag as shown and described.

DESCRIPTION

FIG. 1 is a top, front, left perspective view of a bag showing
our new design;

FIG. 2 is a front view thereof;

FIG. 3 is a rear view thereof;

FIG. 4 is a left side view thereof; and,

FIG. 5 is a right side view thereof.

The dashed lines depict portions of the bag that form no part
of the claimed design. The dotted lines and zig-zag lines
depict stitching that forms no part of the claimed design.

1 Claim, 5 Drawing Sheets

Related U.S. Application Data

continuation of application No. 29/663,667, filed on Sep. 18, 2018, now Pat. No. Des. 887,699.
